US0D1099113S

(12) **United States Design Patent** (10) Patent No.: **US D1,099,113 S**
(45) Date of Patent: ** Oct. 21, 2025

(54) **DISPLAY SCREEN OR PORTION THEREOF
WITH GRAPHICAL USER INTERFACE**

(71) Applicant: **Salesforce, Inc.**, San Francisco, CA
(US)

(72) Inventors: **Jose Lejin P J**, Bengaluru (IN);
Ramanjaneyulu Y Talla, Bangalore
(IN)

(73) Assignee: **Salesforce, Inc.**, San Francisco, CA
(US)

(**) Term: **15 Years**

(21) Appl. No.: **29/835,978**

(22) Filed: **Apr. 22, 2022**

(51) LOC (15) Cl. **14-04**

(52) U.S. Cl.

USPC **D14/487**

(58) **Field of Classification Search**

(57) **CLAIM**

The ornamental design for a display screen or portion
thereof with graphical user interface as shown and
described.

DESCRIPTION

The FIGURE is a front view of a display screen or portion
thereof with graphical user interface showing the claimed
design.

The outer broken lines in the FIGURE show a display screen
or portion thereof, and form no part of the claimed design.
The other broken lines in the FIGURE show portions of the
graphical user interface that form no part of the claimed
design.

1 Claim, 1 Drawing Sheet
